UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

PROCESS OF HERMETICALLY CLOSING SARDINE-CANS.

1,200,282.

Specification of Letters Patent.

Patented Oct. 3, 1916.

Application filed October 18, 1911. Serial No. 655,375.

To all whom it may concern:

Be it known that I, GEORGE W. WEBER, a citizen of the United States, residing in New York, in the county of New York and State of New York, have invented a new and useful Improvement in Processes of Hermetically Closing Sardine-Cans, of which the following is a specification.

This invention relates to a process of hermetically closing cans, and especially cans containing oily products, such as sardines.

The invention consists in coating a flanged can body and its flanged cover interiorly with a coating of protective lacquer, baking the same thereon, filling the can, allowing the lacquered surfaces to become oiled and then uniting the lacquered surface of the cover to the lacquered surface of the body by heat and pressure and holding the united surfaces together until cold.

In the accompanying drawings which form a part of this specification, Figure 1 is a sectional view of a can body and its cover. Fig. 2 is a sectional view of the interiorly lacquered filled can and its cover in the act of being united by heat and pressure. Fig. 3 is a sectional view of the completed product, the lacquered, filled, hermetically sealed can, and Fig. 4 is a sectional view of a double seam of the ordinary type, showing diagrammatically a way of applying heat to the seam, or heat and pressure.

Sanitary reasons have suggested the widespread employment of a protective lacquer for the interior of cans containing food products, and such lacquering has been found desirable in the canning of sardines and such oily food products, containing sometimes olive oil, and sometimes cotton seed oil. Such cans have usually been hermetically sealed by means of soldered seams, though sometimes such sealing is effected by means of folded seams with an interposed gasket of some gummy composition.

I have discovered by experiment, and herein this invention consists, that if both surfaces of the joint be coated with the ordinary protective baked-on lacquer, such as used for coating the interior of food product vessels and the caps or covers therefor, and which is baked on, and such surfaces oiled, as, for example, with the oil contained in filled sardine cans, and pressed

together and heated, the joint will unite into a perfect, hermetic seal, sufficiently strong and sound for the purpose of preserving the contents of the can.

In the accompanying drawing, A represents a common sardine can made with the flange *a*.

B is the can cover made with the flange *b* extending beyond the can flange sufficiently so that it may be turned under same to hold the cover firmly to the can, as shown in Fig. 3.

C is the ordinary protective coating of lacquer applied to the interior of the can and the cover and baked thereon. It will be sufficient if this protective coating is applied to the interior surfaces of the flanges of the can and cover, but I prefer to coat the entire interior of the can and of the cover. This protective coating is baked on the can and cover in the usual way well known to those skilled in the art of coating the interior of food product cans with a protective lacquer.

After the can and its cover have been thus coated and the coating baked on, the can is filled with sardines and oil or any desired food product, the lacquered surfaces of the flanges of the can body and can cover being oiled and the can body and can cover brought together and preferably secured together by folding one of the flanges over the other, as, for example, the flange of the cover over the flange of the can body to hold the two together. After the two flanges are brought together, heat and pressure are simultaneously applied to the two flanges, as, for example, by placing the filled covered can in a support D and bringing a gas heated pressure plate E down upon the joints so supported until the heat and oil have acted together to soften the baked lacquer upon the two joined surfaces pressed together, after which the joint is allowed to cool while still held firmly together, which results in a sound, hermetically joining of the cover and body, sufficient to preserve the contents.

I mention in the foregoing that it is desirable to soften the baked lacquered surface by application of oil or similar substance prior to closing the seam and sealing. I do not wish it understood that this is essential, since, in practising this art, it has been found that, if, after a seam is closed in the

ordinary manner, a heated means, such, for instance as a roller, is applied to the seam and the seam heated to a higher temperature than was used in baking the lacquered coating on the tin, previous to making the seam, the same hermetic joint is obtained, of like durability and efficiency as was obtained by applying a softening oil or such substance to the surfaces before closing the seam.

10 It is also to be noted that this method is also adapted to the sealing of filled cans of any description and particularly to that type known to the trade as sanitary or open 15 top cans, which are closed by means of a seam generally known as a double seam.

16 This type of can is marketed in various ways, for certain purposes cans being provided with a protective lacquer coating, 20 which covers the insides only, while for other purposes, cans are provided with a protective lacquer coating covering the entire can both inside and outside. Thus, in the latter type, does this method of sealing excel, since every surface of the folded double seam, as shown in Fig. 4, is provided with a protective coating which, when subjected to heat under proper conditions, results in a sealing means and produces hermetic joints, without the addition of extraneous sealing compounds or solders.

30 I claim:

1. The process of hermetically sealing cans made of sheet metal and comprising body and cover members having coöperating seam forming flanges, which consists in providing the contacting portions of the seam forming flanges with a baked coating of lacquer, softening the baked lacquer by means of a softening agent, securing the cover to the body by an interfolded seam, and applying heat to the seam, substantially as specified.

2. The process of hermetically sealing 45 cans formed of sheet metal and comprising

ing body and cover members having coöperating seam forming flanges, which consists in providing the contacting portions of the seam forming flanges with a baked coating of lacquer, softening the baked lacquer by means of a softening admixture, securing the cover to the body by an interfolded seam and applying heat to the seam, substantially as specified.

3. The process of hermetically sealing 55 cans made of sheet metal and comprising body and cover members having coöperating seam forming flanges, which consists in providing the contacting portions of the seam forming flanges with a baked coating of lacquer, softening the baked lacquer by means of a softening agent, securing the cover to the body by an interfolded seam, and applying heat and pressure to the seam, substantially as specified.

20 4. The process of hermetically sealing cans formed of sheet metal, and comprising body and cover members having coöperating seam forming flanges, which consists in providing the contacting portions of the 70 seam forming flanges with a baked coating of lacquer, softening the baked lacquer by means of a softening admixture, securing the cover to the body by an interfolded seam and applying heat and pressure to the seam, substantially as specified.

25 5. The process of hermetically sealing cans formed of sheet metal, and comprising body and cover members having coöperating seam forming flanges, which consists in 80 providing the contacting portions of the seam forming flanges with a baked protective coating, softening the protective coating by means of oil, securing the cover to the body by an interfolded seam, and applying 85 heat to the seam, substantially as specified.

GEORGE W. WEBER.
